UNITED STATES PATENT OFFICE.

ALEXANDER K. RARIG, OF COLUMBUS, OHIO.

VALVE FOR BLOWING-ENGINES.

SPECIFICATION forming part of Letters Patent No. 753,159, dated February 23, 1904.

Application filed March 2, 1903. Serial No. 145,733. (No model.)

To all whom it may concern:

Be it known that I, ALEXANDER K. RARIG, a citizen of the United States, residing at Columbus, in the county of Franklin, State of Ohio, have invented certain new and useful Improvements in Valves for Blowing-Engines, of which the following is a specification.

My invention relates to certain improvements in air-discharge valves located between the pumping-cylinder and the receiver in a blowing-engine or air-pump. For reasons pertaining to efficiency in compressing action it is desirable to have valves for this purpose arranged to open when the air on the compression side of the valve reaches the pressure or density of the air on the receiver side of said valve and to close the instant the compressing-piston reaches the end of its compressing stroke. These actions will not follow with an ordinary arrangement of valve operating under the mere unbalance of pressures on opposite sides of the valve, and hence it has been proposed heretofore to employ mechanism for positively imparting the desired movements to the valve at the proper time. It has also been proposed to control movements thus imparted by the pressure in the pumping-cylinder; but arrangements of this kind have proven objectionable or not entirely satisfactory by reason of the possibility of disarrangement in the mechanism which imparts movements to the valve and consequent failure of the valve to act at the proper time. My present invention seeks to avoid damage from this failure of positive operation; and accordingly it consists in certain features of construction whereby the air-discharge valve is rendered semi-automatic in its operation in the sense that if the operating mechanism does not act at the proper time the weight of the valve is balanced or sufficiently removed to permit it to open under slight excess of pressure on the pumping side of the valve, this being accomplished by a specially-constructed valve-piston having controlling connection with the valve working in a valve-piston cylinder and having its weight, together with that of the valve, balanced or relieved at the proper time through the action of pressure communicated to and exhausted from

said cylinder through a passage opening into the main compression-cylinder at an intermediate point which is passed by the main compression-piston in its reciprocating movements. In other words, at the periods named 55 pressure in the valve-piston cylinder becomes such that it overcomes the tendency of the valve to remain closed or so nearly overcomes it that the valve will open automatically before the development of any undesirable excess of pressure on the pumping side of the valve over that on the receiver side. This action I have herein referred to as "balancing the valve."

My invention further consists in certain 65 novel details of construction incident to the carrying out of the objects above stated.

In the accompanying drawings, Figure 1 is a vertical section through the air-discharge valve and a portion of the compression-cylinder of a blowing-engine, the section being taken in the plane of the axis of the valve. Fig. 2 is a top plan view of the valve-casing, the protruding portion of the valve-stem and the overgear or positive operating mechanism 75 for the valve being omitted.

1 represents a portion of the main compression-cylinder. The major portion of this cylinder, the pumping-piston, and the air-inlet valves are omitted, as it is to be understood that these parts may be of any approved known construction and that their specific construction has no particular bearing upon the present invention. It is also to be understood that if the blowing-engine is to be made 85 double-acting, as is usually the case, the valve in which my present invention resides and which is now to be described will be duplicated at the bottom or opposite end of the pumping-cylinder with slight changes. 90

3 represents the valve, which is seated at 4 in the cylinder-head. It is desired to have this valve open when the pumping-piston reaches a position which it occupies when the air has been compressed to the density of the 95 air in the receiver 2, which position may be indicated approximately by dotted lines at α , and to close when the piston reaches the limit of its stroke in the cylinder 1 in order to avoid loss of work accomplished, which would 100

occur if the valve seated after the piston had receded. These movements of the valve are normally imparted by a suitable valve-gear connected with other working parts of the engine and timed to impart the movements at proper moments. Any suitable form of valve-gear may be employed. While it forms no part of my present invention, I have suggested in outline a valve-gear consisting of a two-armed lever α , fulcrumed at b , having an arm c for connection with the working part of the engine, and another arm d , whose pin e engages with the cam-slot f of the lever g . The lever g is mounted on a shaft h , which also carries a shorter arm i , whose pin k is connected by a link l with the pin m on the cross-head n , that is fixed on the valve-stem 10. Positively-operating valve mechanism may fail to act at times with serious results. Hence I have provided the following means for rendering the valve automatic under such conditions. The valve is guided in its vertical movements by a piston 5, working in a cylinder 6, said piston having suitable packings—such, for instance, as shown at 7 and 8—and containing within it a head 9. The head 9 is formed integrally with or otherwise fixedly connected to the valve-stem 10, which extends upwardly for connecting with the valve-gear that positively operates the valve under normal conditions. The piston 5 is fixedly connected with the valve 3. The valve-stem 10 on the piston 5 through the medium of its head 9 positively engages the piston 5 in the direction of unseating the valve; but the recess in the piston 5, which receives the head 9, would permit downward movement of the valve-stem relatively to its valve; but a nest of springs 11 is introduced between the head 9 and the valve 3, which hold said valve and its stem normally in fixed relation, so that the valve will partake of the reciprocating movements imparted to the valve-stem by the valve-gear. It will be seen, however, that the valve and its stem are held in this normal relation by yielding force, so that when the valve is seated by the valve-gear operating positively upon the stem the stroke is cushioned; also, should the positively-actuating valve-gear fail to act or become disarranged, so that the valve-stem 10 is not moved at the proper time in the direction of unseating the valve or should be held stationary the valve may rise under the influence of other forces independently of the valve-stem 10 and the head 9, the springs 11 being compressed in such a case. In other words, the yielding connection between the valve and its stem, by which it is positively actuated, will permit the valve to operate automatically in the event that the positively operating mechanism fails. Yielding thus having been provided for, the automatic action of the valve might occur when a sufficiently great excess of pressure on the compression side of the valve as com-

pared with that on the receiver side of the valve is developed by the pumping or compression piston; but this unbalance of pressures on opposite sides of the valve would ordinarily have to be very great in order to overcome the weight of the valve, the load imposed by the springs 11, and the friction of the parts, and this would be very undesirable for obvious reasons. It is therefore desirable to balance the valve—that is to say, to overcome or nearly overcome the tendency of the valve to remain closed under its weight (if the valve seats downward) and the load of springs 11 and any other influences that tend to hold it in its seated position in the event that it becomes necessary for it to act automatically, so that it will open under very slight unbalance between the pressures on its opposite sides.

For the last-named purpose a pipe 12, communicating with the blowing-cylinder at 13, leads to a port 14 in the cylinder 6, which port communicates, through an annular passage 16 and vertical bores 17, with the open end of the chamber 5^a, in which the head 9 works. So long as the pumping-piston is on the opposite side of the opening 13 from the valve 3 the pressure developed by said pumping-piston is communicated through pipe 12 to the valve-balancing piston 5; but as soon as the blowing-piston passes the opening 13, moving toward the valve 3, the pipe 12 and through it the balancing-piston 5 are in communication with the suction side of the blowing-piston whose cylinder is taking in air at atmospheric pressure, and hence the balancing-piston 5 is relieved of the valve-balancing pressure within it, and the valve 3 is free to resume its seat under the pressure of the springs 11. This condition also continues during the stroke of the blowing-piston away from the valve 3, since after reversing its direction the pumping-piston almost immediately passes the opening 13, so that the pipe 12 still communicates with a suction side of the pumping-piston. Again, reverting to the stroke of the pumping-piston toward the valve 3, it is to be understood that pressure transmitted through pipe 12 when the pumping-piston reaches the position shown by dotted lines α will be equal to the pressure in the receiver, and the superficial area of the parts is so determined that under this pressure in cylinder 6 the load imposed upon the valve by springs 11 and the weight of said valve, with its piston, are so balanced that if the valve-gear does not open the valve 3 at this moment any increase in the pressure on the blowing side of the valve 3, due to further movement of the pumping-piston, will open the valve 3, moving it, with its piston, in a direction away from the seat independently of the valve-stem 10 and head 9, which are being held stationary by the improperly-timed or otherwise disarranged positively-acting valve-gear, this relative movement between the valve and its stem compressing the springs 11. It is to be un-

derstood that the pressure communicating through the bores 17 readily enters between the head 9 and the piston 5; but as soon as the pumping-piston has passed the opening 13 in 5 moving toward the end of the cylinder and pressure is exhausted from the piston 5 the springs 11 will immediately return the valve 3 to its seat. As the upward movement of the valve 3 takes place when the air in the compression-cylinder exceeds in density the air in 10 the receiver, while the seating of the valve 3 takes place instantly at the end of the compression-piston's stroke when air-pressure on opposite sides of the valve has equalized and 15 before there is any unbalance between these pressures, due to the back stroke of the piston, it follows that the movements of the valve 3 are not effectively opposed by the air in the cylinder or receiver.

20 The conditions above described are present in the working of the valve 3 only when the valve-gear fails, since the head 9, with its stem 10, moves with the piston 5 during the ordinary operation of the valve by the valve-gear, 25 and pressure supplied to the piston 5 produces no effect. It will therefore be seen that I have provided valve-controlling means semi-automatic in its character in that it will be positively operated under ordinary conditions by 30 mechanism provided for that purpose; but in the event of failure in the operation of the latter the valve will operate automatically under excess of pressure beneath it.

Having thus described my invention, the following is what I claim as new therein and desire to secure by Letters Patent:

1. In a blowing-engine, the combination with the valve between the compression-cylinder and the receiver and the positively-acting 40 valve-gear therefor; of a yielding connection between the valve and its gear, a pressure-actuated valve-balancing piston connected with the valve, and means communicating pressure to the valve-balancing piston from the compression-cylinder.

2. In a blowing-engine, the combination with the valve between the compression-cylinder and the receiver, and the valve-gear for normally opening said valve; of a piston connected with said valve, and a cylinder in which 50 said piston works, having communication with the compression-cylinder and receiving pressure therefrom to counterbalance the closing tendency of the valve when the valve-gear fails to act.

3. In a blowing-engine, the combination with the valve between the compression-cylinder and the receiver, and the valve-gear normally actuating said valve; of a valve-piston 60 connected with the valve, a valve-piston cylinder in which the valve-piston works, and a communication between said valve-piston cylinder and a point in the compression-cylinder between the limits of motion of the pumping-piston, whereby pressure is communicated to

and exhausted from the valve-piston cylinder by the pumping-piston.

4. In a blowing-engine, the combination with the valve between the compression-cylinder and the receiver, and the valve-gear for 70 normally operating said valve; of a valve-stem through which said gear is connected to the valve, having yielding connection with the valve, a valve-piston surrounding said stem, a cylinder in which said valve-piston works, 75 and a communication between the cylinder of the valve-piston and the compression-cylinder, whereby pressure is supplied to balance the valve.

5. In a blowing-engine, the combination of 80 the valve between the compression-cylinder and the receiver, a balancing-piston connected with said valve, a cylinder in which said balancing-piston works, and by which the valve is guided in its movements, a valve-stem working 85 through said piston and having yielding connection with the valve and suitable valve-gear normally operating the valve through said stem.

6. In a blowing-engine, the combination of 90 the valve located between the compression-cylinder and the receiver, a balancing-piston connected with said valve, a cylinder in which said piston works, a valve-stem moving said valve in the direction of opening, springs interposed between the valve-stem and the valve through which the stem may close the valve, a suitable valve-gear controlling the valve through said stem, and communication between the balancing-piston cylinder and the 100 pressure-cylinder of the engine.

7. In combination with a valve for blowing-engines, the balancing-piston connected with said valve, the cylinder in which said balancing-piston works, the positively-actuated 105 valve-stem working through said piston and having a head thereon working in said piston, a passage establishing communication from the compression-cylinder to the space between the head and piston.

8. In combination with a valve for blowing-engines, the balancing-piston connected with said valve, the cylinder in which said balancing-piston works, communicating with main compression-cylinder, the positively-actuated 115 valve-stem for said valve, a head on said valve-stem, springs interposed beneath said head, closing the valve, and a passage communicating pressure from the balancing-piston cylinder to the space between the head and piston.

9. In a blowing-engine, the combination of the valve located between the compression-cylinder and the receiver, the balancing-piston connected with said valve, the cylinder in which said balancing-piston works, having 125 communication with the compression-cylinder, the valve-stem extending through and having a head working in said balancing-piston, and engaging the piston in one direction through the medium of said head, pressure- 130

communicating passages between the balancing-piston cylinder and the space between the head and piston, springs interposed between the head and the valve, and positively-acting 5 valve-gear connected with the valve-stem.

10. In a blowing-engine, the combination of the valve located between the pressure-cylinder and the receiver, a valve-balancing cylinder, a piston working in said cylinder connected with the valve, and having a pressure-chamber between its ends, a valve-stem extending through the piston and having a head working in the piston, passages communicating between the pressure-chamber in the 15 piston and the space between said piston and head, springs located between the head and the valve, positively-acting valve-gear connected with the valve-stem, and a suitable communication between the pressure-chamber 20 of the piston and the compression-cylinder of the blowing-engine.

11. In a blowing-engine, the combination of the air-discharge valve, valve-gear therefor, a cylinder arranged in line with said air-valve, 25 a piston working in said cylinder, connected with the air-valve, a valve-stem extending through said piston and having a head working in the piston, a passage supplying pressure from the main compression-cylinder to 30 the space between the valve-piston and the

head; the superficial area of the valve-piston exposed to pressure being such that the weight of the piston and valve is balanced when the valve-gear fails to operate, thereby permitting the valve to rise under increase of pressure beneath it. 35

12. In a blowing-engine, the combination of the air-discharge valve, valve-gear therefor, a cylinder arranged in line with said air-valve, a piston working in said cylinder, connected 40 with the air-valve, a valve-stem extending through said piston, and having a head working in the piston, springs interposed between said head and the valve, and a passage supplying pressure from the main pumping-cylinder to the space between the valve-piston and the head; the superficial area of the valve-piston exposed to pressure being such that the weight of the piston and valve, and the pressure of said springs, are balanced when the 45 valve-gear fails to operate, thereby permitting the valve to rise under increase of pressure beneath it. 50

The foregoing specification signed this 19th day of February, 1903.
